UNITED STATES PATENT OFFICE

167,562

FISHLINE STORAGE REEL

Frank Diebold, San Francisco, Calif.

Application January 26, 1952, Serial No. 18,250

Term of patent 7 years

(Cl. D31—4)

To all whom it may concern:

Be it known that I, Frank Diebold, a citizen of the United States of America, resident of the city and county of San Francisco, State of California, have invented a new, original, and ornamental Design for a Fish Line Storage Reel, of which the following is a specification, reference being made to the accompanying drawings, forming a part thereof.

Fig. 1 is a side elevation of a fish line storage reel, embodying my new design;

Fig. 2 is an edge elevation; and

Fig. 3 is a cross sectional view taken on the line 3—3 of Fig. 1.

The fish line storage reel embodying my new design is characterized by the surface ornamentation shown thereon.

I claim:

The ornamental design for a fish line storage reel, substantially as shown and described.

FRANK DIEBOLD.
